NASAL APPLIANCE

Chester Arthur Smith, Jr., 417 B St., Clifton Forge, Va.
Filed Apr. 12, 1962, Ser. No. 186,932
1 Claim. (Cl. 128—76)

The present invention relates to a nasal appliance in the form of a brace for changing the appearance and contour of the human nose.

An object of the present invention is to provide a nasal appliance or brace for the purpose of changing the contour of a human nose so that the person has a more pleasing appearance.

Another object of the present invention is to provide a nasal appliance which is easily inserted into and withdrawn from either of the cavities or both of the cavities of the human nose, one which can be worn comfortably and without distress, one which is very effective in changing the contour of the human nose so as to improve the appearance of the human, and one which may have lasting effects in changing the contour of the nose.

A further object of the present invention is to provide a nasal appliance or nose correction brace which may be manufactured in quantity at reasonable cost from plastics, stainless steel, and the like, one which is substantially obscured from view when worn by a human, and one which is highly effective in action.

These and other objects and advantages of the present invention will be fully apparent from the following description when taken in connection with the annexed drawing, in which:

FIGURE 1 is a side elevational view of a portion of a human face, showing the nasal cavity and nose partially in section,

FIGURE 2 is a view on an enlarged scale, taken on the line 2—2 of FIGURE 1,

FIGURE 3 is a view partially in section of the device removed from the human nose,

FIGURE 4 is a view taken on the line 4—4 of FIGURE 3,

FIGURE 5 is a view taken on the line 5—5 of FIGURE 3,

FIGURE 6 is a side elevational view of the device of the present invention,

FIGURE 7 is an enlarged view of the device showing it on the end of a special tool for insertion in the nose, and

FIGURE 8 is a view taken on the line 8—8 of FIGURE 7.

Referring in greater detail to the drawing, in which like numerals indicate like parts throughout the several views, the reference numeral 10 in FIGURE 1 designates generally the human nose and the reference numeral 12 designates one of the cavities of the nose 10.

The device of the present invention is designated generally by the reference numeral 14 and it consists in a housing 16 having one end closed by a plate 18 and having the other end provided with an opening 20.

A compressible and expandable spring 22 is disposed within the housing 16 and has one end abutting the plate 18 and has its other end inwardly and spaced from the open end of the housing 16.

2

A plunger 24 extends slidably through the opening 20 and has a head 26 on one end abutting the end of the spring 22 remote from the plate 18.

On the other end of the plunger 24 remote from the head 26 is a flat protuberance 28 sealed within a resilient pad 30 partially offset with respect to the longitudinal axis of the plunger 24, as shown in FIGURE 4.

The end plate 18 is also covered with a pad 32 fabricated of rubber, soft plastic or the like. The pad 30 is similarly fabricated.

The housing 16 is of rectangular cross-sectional configuration and the head 26 is conformably shaped to fit within the housing 16. Preferably the spring 22 is fabricated with flat sections entirely filling the housing 16 below the head 26, as shown in FIGURE 2.

The plunger 24 is provided with a hole or recess 34 adjacent the protuberance 28 and the housing 16 is provided with a hole 36 on the same side of the housing 16 as the hole 34.

As shown in FIGURE 7, the hole 34 and the hole 36 receive the free ends of the legs 38 and 40 of a bifurcated tool 42, such as a pair of tweezers or the like, so that the plunger may be forced to the dotted line position by compressing the legs 38 and 40 together and for manipulating the device of the present invention into the nostril of a human being as shown in FIGURE 1.

In use, one of the devices of the present invention is inserted in each cavity in the human nose and this may be done by either using the tool 42 or using the fingers as preferred. As shown in FIGURE 1, the device expands to press the flesh of the forward part of the nose outwardly to change the contour of the nose. The arcuate curve of the housing and plunger is such that the device may be inserted against the wall of the nose and when so inserted it will be relatively inconspicuous and will conform to the shape of the cavity without interfering with the breathing of the individual employing the same.

What is claimed is:

40 A nasal appliance comprising a housing having one end closed and the other end open, a compressible and expandable spring disposed within said housing and having one end abutting the closed end of said housing and having the other end inwardly of and adjacent the other end of said housing, a plunger extending slidably through the open end of said housing and having one end in abutting engagement with said other end of said spring, a first resilient pad on the other end of said plunger, said pad being partially offset with respect to the longitudinal axis of said plunger, and a second resilient pad on the closed end of said housing, said housing and said plunger each being provided with a hole for the insertion therewith of the free end of the leg of a bifurcated tool.
